UNITED STATES PATENT OFFICE.

ELLSWORTH A. HAWTHORNE, OF BRIDGEPORT, CONNECTICUT

LAMP.

1,242,186.

Specification of Letters Patent.

Patented Oct. 9, 1917.

Application filed May 8, 1917. Serial No. 167,184.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Lamps, of which the following description, in connection with the accompanying drawings, is a specification, like characters on the drawings representing like parts.

This invention relates to lamps, and is more particularly concerned with means for facilitating the assembling and fastening together of the glazing and lamp door or 15 bezel of the lamp casing.

My invention will be best understood by reference to the following description, when taken in connection with the accompanying drawings of one specific embodiment thereof, 20 while its scope will be more particularly pointed out in the appended claims.

In the drawings:

Figure 1 is a central, longitudinal, sectional view of a lamp embodying my invention;

Fig. 2 is a detail central, longitudinal section of some of the parts shown in Fig. 1, illustrating the mode of assembling;

Figs. 3 and 4 are details of one of the 30 nuts with its clamping means;

Fig. 5 is a sectional view on line 5—5 of Fig. 1; and

Figs. 6 and 7 are detail views of one of the glazing retaining elements.

Referring to the drawings, and to the embodiment of my invention which I have selected for illustration, I have there shown a lamp comprising a suitable light source 8 associated with an appropriate reflector 9, 40 both mounted within a casing comprising a body 10 and a door or bezel 11, the latter having a seat 12 for a glazing or light-transmitting element 13. The bezel or door 11 is herein provided with an annular groove 14 to receive a strip of suitable packing material 15, such as felt, which may be and preferably is coated on both sides with shellac before being put in place. The seat 12 may be and preferably is inclined with relation to the face of the glazing 13, and is resilient so that when the glazing is subjected to sufficient pressure, the seat will flex and accommodate itself to the surface of the glazing, and thus produce a tight moisture and dust excluding joint. It will be understood, of course, that the packing strip

15 is initially of such thickness as to be compressed when the glazing 13 is brought against its seat.

As a means for holding the glazing seated 60 against its seat, I have herein provided means including a plurality of screws 16, extending radially through the circumferential wall of the door or bezel 11 to the interior of the latter, where they have screw-threaded engagement with suitable nuts 17. Carried by and preferably formed integral with each of the nuts 17 is an arm 18, engaging the internal surface of the circumferential walls of the door or bezel 11, and 70 constituting a sort of fulcrum for the nut 17. Also carried by and preferably formed integral with the nut 17 is an arm 19, constituting a wedging means co-operating with a suitable shoulder 20 within the door or 75 bezel 11. This shoulder may be otherwise suitably formed, but herein is formed as a part of an annular groove 21, within a bead 22.

Carried by and preferably formed integral with each nut 17 is an arm or pair of arms 23 extending inwardly in a direction generally opposite to that of the arm 19, and so arranged that by turning the screw 16 in the proper direction, the arm 23 urges the 80 glazing 13 toward its seat 12. The arms 23 may, if desired, directly engage the glazing 13, but I prefer to provide one or more, herein a plurality of retaining elements 24 interposed between the arms 23 and the 85 single face of the glazing 13. Each of these elements may, and preferably does, interlock with its respective nut 17, and to this end, as herein shown, each plate is provided with an integral arm or lug 25 interposed 90 between the arms 23, as will be evident from a comparison of Figs. 1 and 5. By this means, the plates 24 are held in their proper positions with relation to their respective nuts 17, and the assembling of the parts is 95 greatly facilitated.

In assembling the parts, the packing strip 15 is first put in place in the manner described, after which the glazing 13 is laid in place on the packing 15. The retaining 105 elements 24 are next laid on the glazing 13, after which the nuts 17 are put in place, and the screws 16 introduced into the circumferential wall of the door or bezel, and screwed into their respective nuts. The inclined arms 19 gradually ride down the inclined shoulder 20, and in this way, the arms

23 are brought to bear with forcible pressure against the retaining elements 24. Preferably, the arms 23 are somewhat resilient, so that in the final position of the 5 paris, said arms are tensioned and hold the glazing against its seat with spring pressure, and in turn cause the seat to flex and insure a tight, dust and moisture excluding joint, yet without danger of breakage of the 10 glazing.

It will thus be seen that the parts will be quickly and conveniently assembled, and that glazings of various thicknesses within reasonable limits can be accommodated, and 15 that even in the case of glazings varying in thickness from one point to another along the margin, the resilient clamping devices provide a means for accommodating all such variations in thickness, without danger of 20 breaking the glazing.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to the specific embodiment herein shown, 25 but that extensive deviations from the illustrated form or embodiment of the invention 30 may be made, without departing from the principles thereof.

Having thus described my invention, what 35 I claim and desire by Letters Patent to secure is:—

1. In combination, a glazing, a casing having a seat therefor, and means to hold said glazing seated against said seat, including 40 a screw extending from the exterior to the interior of said casing, a nut having screw-threaded engagement with said screw within said casing, an arm carried by said nut and having interlocking engagement with said 45 casing and another arm carried by said nut and arranged to urge said glazing against said seat.

2. In combination, a glazing, a casing having a seat therefor, and means to hold said 50 glazing seated against said seat, including a screw extending from the exterior to the

interior of said casing, a nut having screw-threaded engagement with said screw within said casing, an arm carried by said nut and having interlocking engagement with said 55 casing, and means having interlocking engagement with said nut and engaging said glazing to urge said glazing against said seat.

3. In combination, a glazing, a casing having a seat therefor, and means to hold said glazing seated against said seat, including a screw extending from the exterior to the interior of said casing, a nut having screw-threaded engagement with said screw within 60 said casing, an arm carried by said nut and having interlocking engagement with said casing, a second arm carried by said nut, and means having interlocking engagement with said second arm and engaging 65 said glazing to urge said glazing against said seat.

4. In combination, a glazing, a casing having a seat therefor, and means to hold said glazing seated against said seat, including 75 a screw extending from the exterior to the interior of said casing, a nut having screw-threaded engagement with said screw within said casing, an arm carried by said nut and having interlocking engagement with 80 said casing, a pair of arms carried by said nut, and means having interlocking engagement with said pair of arms and engaging said glazing to urge said glazing against 85 said seat.

5. In combination, a glazing, a casing having a seat therefor, and means to hold said glazing seated against said seat, including a screw extending from the exterior to the interior of said casing, a nut having screw-threaded engagement with said screw within 90 said casing, an arm carried by said nut and having interlocking engagement with said casing, a pair of arms carried by said nut, and a plate engaged by said pair of 95 arms and urged thereby against said glazing, said plate being provided with an arm embraced by the arms of said pair.

In testimony whereof, I have signed my name to this specification.

ELLSWORTH A. HAWTHORNE.
